UNITED STATES PATENT OFFICE.

CHARLES ALBERT DIES, OF CHICAGO, ILLINOIS, ASSIGNOR TO CLAYTON MARK, OF CHICAGO, ILLINOIS.

METHOD OF MAKING PIPE-COUPINGS.

1,265,709.

Specification of Letters Patent.

Patented May 7, 1918.

Application filed February 15, 1912. Serial No. 677,789.

To all whom it may concern:

Be it known that I, CHARLES ALBERT DIES, a citizen of the United States, and a resident of Chicago, Cook county, Illinois, have invented a new and Improved Method of Making Pipe-Couplings, of which the following is a specification, reference being had to the accompanying drawings, in which—

Figures 1 to 7 show in section the steps employed in making the coupling ring or nut of the coupling: in Fig. 1 the blank in position for the first forming operation; in Fig. 2 the blank after the first operation; in Fig. 3 the blank being ejected from the dies; in Fig. 4 the blank in position for the second forming operation; in Fig. 5 the blank after the second forming operation; in Fig. 6 the blank ready for the final operation; and in Fig. 7 the coupling ring formed in final shape. Fig. 8 is a section on lines VIII—VIII of Fig. 7, showing the hexagonal shape of the die; Fig. 9 is a section of the coupling nut, and Fig. 10 is an elevation thereof. Figs. 11 to 15 show the various steps employed in making the spud or head-piece: in Fig. 11 the blank ready for the first forming operation; in Fig. 12 the blank after the first forming operation; in Fig. 13 the blank in position for the second forming operation; in Fig. 14 the blank after the second operation is completed; and in Fig. 15 the final operation and the spud or head-piece in final form. Fig. 16 shows a section of the spud or head-piece, and Fig. 17 an elevation thereof. Figs. 18—19 show the final forming operation of the tail-piece (the first two operations being similar to those shown in Figs. 1—7): in Fig. 18 the blank is in position for the final operation, and in Fig. 19 the final operation and the completed tail-piece. Fig. 20 is a section of the tail-piece and Fig. 21 is an elevation thereof. Fig. 22 shows in section the complete coupling.

My invention relates to pipe couplings or pipe unions, and is designed to provide a coupling or union made from sheet metal or seamless tubing. My improved union is exceedingly durable, is adapted for very high pressures, is very efficient in service, and at the same time is economical from the standpoints of cost and longevity.

Referring to the drawings, and first to the formation of the coupling nut, A is the blank, preferably a sheet of rolled steel,

which rests on the pilot 2 and between the jaws 3 of the die 4. The die 4 is recessed to permit the reception of the punch 5, and located in this recess 6 is the die-plate 7, which acts as an ejector and is operated by the pins 8. The punch 5 has a circular opening 9 having a diameter somewhat larger than the diameter of the pilot 2 of the die 4 to provide room for the admission of, and the shaping of the blank A therebetween. In the opening 9 the knock-out 10 operates and is reciprocated on a shaft 11.

In Fig. 4 the die 12 has an ejector ring 13, the upper face 14 of which is beveled from its outer edge toward the centrally located pilot 15. The co-acting punch 16 has its surface 17 beveled to correspond to the bevel of the face 14 of the ring 13. 18 is the knock-out of the punch 16.

In Figs. 6 and 7 the die 19 has a central aperture 20 which permits the discharge of the cut-out portions of the metal. Around the mouth of this aperture 20 the die 19 is recessed to afford a seating surface 21 for the blank A². 22 is the punch having a centrally disposed cutter 23 and a knock-out ring 24, which reciprocates in the hexagonally shaped throat 25.

In Figs. 11 and 12, 26 is the die having a throat 27 therein in which is located a centrally disposed pilot 28 having a larger lower portion 29. 30 is the ejector ring positioned in the throat 27. The punch 31 has a central opening 32 having its inner portion 33 constricted to form faces corresponding to the face of the pilot 28 and its lower portion 29. 34 is the knock-out of the die 31.

In Figs. 13 and 14 the anvil 35 has a central opening 36 having a restricted lower portion 37 in which is located the ejector 38. The face 39 of the anvil 35 is inclined inwardly and upwardly from its outward edge toward the opening 36. The die 40 has the outer face 41 of the knock-out 42 inclined inwardly and upwardly to correspond to the face 39 of the anvil 35, and a centrally disposed depending punch 43 with narrow lower portions 44, and a cutting face 45 which cuts out the bottom of the blank B'.

In Fig. 15 the holder 46 has a recess 47 in which is located the anvil 48 having a narrowed upper pilot portion 49 and beveled surface 50 therebetween. The anvil 48 also acts as an ejector. The die 51 has a

knock-out 52, a central pilot 53 and a throat 54 between the knock-out 52 and the plunger 53. The nose 55 of the knock-out 52 is of such diameter that it will enter freely 5 into the mouth of the recess 47 between the holder 46 and the pilot 49.

In Figs. 18 and 19 the anvil 56 has an annular recessed portion 57, and the die 58 has annular throat 59, and a bevel-nosed 10 pilot 60 within the throat 59. 61 is an ejecting ring operating in the throat 59.

My preferred manner in making the coupling nut, spud or head-piece, and tail-piece is as follows:

15 For the coupling nut I take a sheet of metal A cut to proper size, place it on the pilot 2 within the jaws 3 of the die 4. I then actuate the punch 5, which draws the metal down over the pilot 2 forming the 20 blank into the cup shape A', comprised of the bottom a, sides a' and rim a', shown in Fig. 3. The punch 5 is then retracted and the ejector plate 7 is simultaneously operated to free the blank A' from the die 25 4. After retraction of the punch 5 I operate the knock-out 10 to free the blank A' from the punch 5. The blank is then ready for the second operation.

In the second operation shown in Figs. 4 30 and 5 the blank A' is positioned on the pilot 15. The punch 16 is then actuated, the metal of the blank is driven downward causing the diameter of the cup to be decreased and the sides a' to be elongated, taking the shape of 35 the pilot 15, and at the same time the flange or rim a² is turned upward by the face 14 of the ring 13, and the blank assumes the shape A² shown in Fig. 5. The ejector 13 is then operated freeing the blank A² from 40 the pilot 15, and subsequently the knock-out 18 is actuated to free it from the punch 16. The blank A² is then inverted and placed on the die 19 shown in Fig. 6. The punch 22 is then actuated and the upper lip of the 45 blank A² is forced into the throat 25 so that the outwardly extending flange a² is bent downwardly until substantially parallel with the sides a'. As the die descends and the upper edge of the blank is forced into 50 the throat 25, the cutter 23 meets the bottom of the blank A² and cuts out a circular portion thereof leaving an inwardly extending lip a³ which acts as a seat or bearing surface for the tail-piece C'. The cut out portion 55 drops down through the aperture 20 which acts as a discharge chute, and the blank is of the shape A³ shown in Figs. 9 and 10. The throat 25 is hexagonal, as shown in Fig. 8, and forms the exterior of the overturned 60 flange portion a² into a wrench seat, as is shown in Figs. 7, 9 and 10. This step completes the forming operations of the coupling ring or nut.

In forming the spud or head-piece, as 65 shown in Figs. 11-15, I take the blank B,

place it on the pilot 28 of the die 26 and between the jaws of the die, and actuate the punch 31 which draws the metal down over the pilot 28 giving it the form of the pilot with a bottom b, sides b', b²—the sides b' 70 being of less diameter than the side b²—and an outwardly extending flange b³, thus assuming the shape of the blank B' shown in Fig. 12. The punch 31 is then retracted, the ejector ring 30 being actuated to free the 75 blank B' from the pilot 28. The blank B' is then freed from the punch 31 by means of the knock-out 34.

The blank B' is then inverted and placed on the anvil 35 and the die 40 is then actuated. 80 The punch 43 forces the blank B' down into the central opening 36 of the anvil 35 until the lower portion of the die is in contact with the ejector 38, at which point a circular opening is cut in the bottom b of 85 the blank B', and the sides b', b² and part of the bottom b are caused to assume the contour of the passage 36 and of its restricted lower portion 37, and the flange b³ is bent downwardly, and the blank thus assumes the form B² shown in Fig. 14. The die 40 is then retracted, the ejector 38 operated to free the blank B² from the anvil 35, and the blank B² is then freed from the punch 43 of the die 40 by means of the 90 knock-out ring 42.

The blank B² is then inverted, placed on the holder 46, shown in Fig. 15, and the die 51 is then brought down on the constricted portion of the blank B, which enters the 100 throat 54. This forces the blank B² down into the throat 47 of the holder 46, bending the flange b³ so that it will be parallel to the sides b², and its exterior surface when threaded will form a bearing surface for 105 the coupling nut A². In the throat 54 is the beveled surface 50 which forms an internal bearing surface b⁴ for the nose of the tail-piece C. During this operation the blank B² is slightly constricted throughout its whole 110 length, and is formed into the shape shown as B³ in Figs. 15, 16 and 17. The die 51 is then retracted and the ejector 48 operated to free the blank B³ from the anvil 46. The knock-out 52 then frees the blank B³ from 115 the die 51. The spud or headpiece is then complete with the exception of threading the bore of constricted portion thereof. If desired, the end of the constricted portion 120 may be upset in any suitable manner.

The first three operations for forming the tailpiece are substantially those shown in Figs. 1 to 7. The blank C is then placed in the annular throat 59 of the die 58 shown in Fig. 18 and is brought into contact with the 125 annular recessed portion 57 of the anvil 56. This action forces inwardly the bent-over portion e of the tail-piece C, thus constricting the opening of the blank as shown in Fig. 19 and forming the nose of the tail- 130

piece and having the surface c' with which the lip a^3 of the coupling nut is intended to coat. The die 58 is then retracted and the tail-piece C is then freed by the operation of the ejecting ring 51, and the article is in the final form shown in Figs. 20 and 21.

The three members are then threaded, and, if desired, the outer ends of the spud and tail-piece may be upset as shown in Fig. 22.

In the herein described method of automatically forming pipe couplings by cold stamping or swaging, I first draw a metal sheet into the form of a seamless cup or tubing, then reduce the tubing by compression, upset and aperture it, and finally compress it into the desired form. Obviously, the order of these operations may be changed at will, although it is not desirable to draw the metal except in the preliminary forming operation. Other changes may also be made by those skilled in the art in the form of the article and the process of making same described and shown herein, without departing from my invention.

What I claim is:

1. The process of making pipe coupling

parts, which consists in cold working a blank by a series of die-reducing operations into a flanged tubular blank, then by longitudinally applied compression bending and compressing the flange downwardly against the exterior of the blank as a reinforcement therefor, and swaging a compressed seat at the juncture of the blank and flange as a bearing for another member of the coupling.

2. The process of making pipe coupling parts, which consists in forming a flat sheet metal blank into tubular form and in flanging one end thereof, bending the flanged portion of the blank outwardly and compressing it downwardly by longitudinally applied compression against the exterior of the blank, so as to present a wall directed axially of the blank and acting as a reinforcement for the body of the blank adjacent the juncture of the flange and the body, and swaging a compressed seat at such juncture as a bearing for another member of the coupling.

CHARLES ALBERT DIES.
